CUSHIONING MECHANISM FOR RAILWAY
VEHICLES

Donald Willison, Cleveland, and Hubert L. Spence,
East Cleveland, Ohio, assignors to National
Malleable and Steel Castings Company, Cleve-
land, Ohio, a corporation of Ohio

Application September 1, 1950, Serial No. 182,750

18 Claims. (Cl. 213—45)

1

Our invention relates to cushioning mechanism for use in draft rigging of railway vehicles and more particularly to rubber cushioned draft gears of the compensating type.

In the copending application of Donald Willison, Serial No. 150,473, filed March 18, 1950, is disclosed a draft gear of the above mentioned compensating type which automatically eliminates all free slack between the cushioning mechanism and the yoke which surrounds the cushioning mechanism, and between the cushioning mechanism and the draft gear pocket.

Our invention, which comprises a novel arrangement of a plurality of rubber pads and related metallic followers, provides various improvements over previous forms of cushioning mechanisms of both the compensating and non-compensating types.

Our cushioning mechanism can be used in A. A. R. freight car construction with any conventional type yoke and with the A. A. R. standard or alternate standard coupler shank.

Our invention provides for more travel and capacity in buff than in draft.

Also, our invention when used in conventional A. A. R. freight car construction, in conjunction with the A. A. R. standard or alternate standard coupler shank, provides greater travel and capacity in buff than that provided for by conventional types of draft gears in use at the present time.

Also, our invention is one that is simple in construction, cheaply manufactured and easily assembled.

Other various features and advantages of our invention will be set forth in the accompanying description taken in conjunction with the drawings in which:

Fig. 1 is a plan view, partly in section, of our draft gear applied to a freight car of conventional construction.

Fig. 2 is a side elevational view partly in section, of our draft gear shown in Fig. 1.

Fig. 3 is a sectional plan view of our draft gear partially compressed in buff.

Fig. 4 is a perspective view of the compensating follower of the draft gear.

Fig. 5 is a typical compression curve illustrating the draft and buffing characteristics of the draft gear shown in Figs. 1-4.

Fig. 6 is a perspective view of the cushioning follower in its assembled relation with the yoke, with a portion of the yoke shown in dot-dash lines.

Fig. 7 is a cross sectional view of the cushion-

2

ing follower showing the manner of assembling the follower in the yoke.

Fig. 8 is a side elevational view, partly in section, showing the preferred method of inserting our draft gear and yoke assembly into the draft gear pocket.

Fig. 9 is a cross sectional view taken along line 9—9 of Fig. 8.

Fig. 10 is a sectional plan view of our draft gear showing means employed to provide an alternate method of insertion of the draft gear and yoke assembly into the draft gear pocket.

Referring to the drawings, and more particularly to Figs. 1 and 2, we have shown the usual car sill construction at 1—1, a draft gear pocket 3 having rear buffering lugs or abutments 2—2 and front draft lugs 4—4, and a draft gear yoke 6 which may be of any conventional type but which for purposes of illustration is an A. A. R. standard vertical plane horizontal key yoke, known as the Y-40.

The shank 7 of the car coupler is connected to the yoke by means of horizontal key 9 which extends laterally through slots 18 in the center sills 1—1 and side walls 19 of the striking casting 5. Slots 18 are of sufficient length that the ends thereof are at no time engaged by key 9 during draft or buffering movements of the coupler and yoke.

Slot 20 in the coupler shank is preferably of slightly greater length than the width of key 9, thus leaving a clearance as at 21 between the key and the forward end of the slot when the mechanism is in neutral position, as in Fig. 1.

The main cushioning unit 8 and the compensating or forward cushioning unit 10 each comprise a group of compression pads 11, preferably of the type claimed in our copending patent application, Serial No. 138,614, filed January 14, 1950. Each pad consists of a metal plate 12 with a cushion of rubber bonded to each face. The surface of the rubber is corrugated as we have found that a cushioning pad of that type combines very desirable compression qualities with a high degree of durability and sturdiness. Each group of pads terminates in end pads 13 which have rubber bonded to one face only, thus avoiding any rubber to metal contact at the working faces of the end pads.

Extending between the front end of the main cushioning unit 8 and the front draft lugs 4—4 is the main cushioning follower 14 comprising a transverse follower acting base portion 14a and a pair of forwardly extending rectangular loop portions 14b integral therewith. Each loop por-

55

tion comprises a pair of horizontal load transmitting arms 14c extending forwardly from the transverse follower acting base portion 14a, and vertical connecting arms 14d having draft lug engaging faces 14e. The vertical spacing of the horizontal load transmitting arms 14c of each loop is substantially the same as the spacing of the yoke arms 26, thus permitting the use of the same dimension rubber pads in the compensating cushioning unit 10 as in the main cushioning unit 8. It will be observed in Fig. 6 that the faces of loop portions 14b lie in vertical planes and are essentially parallel to one another. Also, the horizontal spacing of the loop portions is such that a passageway is provided for the upper and lower yoke arms 26. It will be noted that yoke arms 26 are overlapped by arms 14e of the loops and in effect are recessed into follower 14.

It will also be observed that the inner sides of arms 14c are bevelled at their forward ends so as to provide clearance for the adjacent head of a yoke during any rearward movement thereof. Although this clearance is not necessary in connection with the type of yoke illustrated, since the yoke is not moved rearwardly in buff, it is necessary when other types of yokes which are moved rearwardly in buff are used with our draft gear. Also, the front surfaces of vertical connecting arms 14d are tapered at the vertical extremities thereof, as at 14g, the reason for which will be hereinafter explained.

Disposed between the front end of the compensating cushioning unit 10 and the end surface 27 of the coupler shank 7, and within the loop portions 14b of the main cushioning follower 14 is the compensating follower 22 which, as best shown in Fig. 4, comprises a base portion 23, and a forward abutment 24 spaced from the base portion 23 by webs 25 and 25a. In the arrangement shown, the forward abutment in yoke 6 is formed by end surface 27 of the coupler shank. In this construction, abutment 24 of the compensating follower engages surface 27. However, it will be understood that other types of yokes which may be used are formed with an integral forward abutment for engagement with the compensating follower. The central web 25a is formed with a pair of shoulders 25b facing end surfaces 17 of the yoke head, for use in connection with the assembly of the mechanism. The base portion 23 is extended laterally of the webs 25 and 25a so as to provide abutment surfaces 28 within the loop portions 14b of cushioning follower 14. It will be noted that the area of base portion 23 is substantially the same as that of base portion 14a of the main follower. The compensating follower is so formed that when the compensating follower is in assembled relationship, as seen in Figs. 1 and 2, the forward face portion 24 thereof is located forwardly of the draft lug engaging faces 14e of the main cushioning follower 14 by an amount indicated at "a" in Fig. 1. Also the abutment surfaces 28 of the compensating follower 22 are spaced rearwardly from the rear surfaces 14c of the vertical connecting portions 14d, thereby providing for forward motion of the compensating follower relative to the main cushioning follower.

ishrdlu shrdlu shrdlu.

It will be observed in Figs. 1 and 2 that the outer sides of horizontal load transmitting arms 14c of the main follower 14 are formed with recesses 14h at the forward extremities thereof,

thus providing shim seats 14i. Also the inner side of base portion 23 of the compensating follower 22 is formed with vertical notches at the lateral extremities thereof to provide shim seats 14j, in opposed relationship to and spaced from shim seats 14i, the use of which will be herein-after described. The lateral depth of the notch is at least equal to and preferably greater than the depth of the recesses 14h in the main cushioning follower.

Disposed between the rearward end of the main cushioning unit 8 and the rear abutment or pulling surface 30 of the yoke 6 is the rear cushioning follower 31 comprising a transverse follower acting portion 32 having a pair of rearwardly extending rectangular projections 33 disposed at the lateral extremities thereof and adapted to engage rear stop lugs 2-2. Follower 31 also has pairs of tapered lugs 38 disposed on the top and bottom sides thereof. The purpose of these lugs will be explained in connection with the assembly of the mechanism. The rear surface 34 of follower acting portion 32 is engaged by the pulling surface 30 of yoke 6. The amount of forward offset shown at "a" in Fig. 1 between the yoke engaging surface 34 and the rear draft lug engaging surfaces 35 is preferably the same as the previously mentioned offset "a" at the forward end of the assembly. Thus the yoke 6 and consequently the coupler shank 7 are offset forwardly of the draft gear pocket in relation to the position they would occupy were it not for this offset construction of our draft gear. Thus the buffing clearance between the coupler horn 15 and the front face 46 of the striking casting 5 is increased correspondingly to allow for the additional buffing travel produced by our draft gear.

Our draft gear is assembled in the yoke and draft gear pocket preferably as follows:

10 The main cushioning follower 14 is inserted between the yoke straps 26, as shown in Fig. 7, and then rotated into its proper position, as shown in Fig. 6. The associated compensating follower 22 is then inserted transversely through the loops of the main cushioning follower.

15 Next the rear cushioning follower 31 is inserted between the yoke arms and moved rearwardly into contact with the pulling surface 30 of the yoke. Then the main group 8 of cushioning pads is inserted between the main cushioning follower and the rear cushioning follower. The yoke containing the parts thus far assembled is placed rear end downward in a press. Sufficient force is then applied to the draft lug engaging faces 14e of the main cushioning follower to compress the cushioning unit 8 so that the compensating follower can be raised a sufficient amount to allow the insertion of the compensating group 10 of cushioning pads. It will be noted that the dimensions of the coupler shank engaging portion 24 of the compensating follower are such that it can be moved forwardly into the rear of the yoke head until its surfaces 28 engage rear surfaces 14c of vertical arms 14d of the main follower, thereby providing sufficient clearance between bases 23 and 14a of compensating follower and the main follower, respectively, for the insertion of a required number of cushioning pads 11 to form the compensating group 10.

20 After the insertion of the group 10 of compensating cushioning pads, the force is released from the draft or stop lug engaging faces 14e of the main follower 14 and is applied to the coupler shank engaging portion 24 of the compensating follower. The force should be sufficient to al-

low for the insertion of shims 37 into recesses 14h at the forward end of the main follower, as shown in Figs. 8 and 9. The force against portion 24 can then be released, whereupon the main cushioning unit 8 expands, thus forcing the shoulders 25b of compensating follower 22 into engagement with rear surfaces 17 of the yoke head.

Shims 37 are formed with wedging surfaces 40. While surfaces 40 are not needed during the gear assembly of the draft gear and yoke in the draft gear pocket, they have a definite use during disassembly of the mechanism, as will be herein-after explained. The thickness of shim 37 is such that the distance across the shims as seen in Fig. 9 is slightly less than the spacing of the car center sills 1-1. The length of shim 37 is sufficient to assure a good bearing against seats 14i and 41 on the main follower and compensating follower, respectively, after the draft gear and yoke assembly has been removed from the press. Also, the width of each shim is such that upon removal of the draft gear and yoke assembly from the press, the compensating follower 22 is so positioned relative to the main follower 14 that the distance "b" shown in Fig. 9 between the forward face portion 24 of the compensating follower and the draft lug engaging faces 14e of the main cushioning follower is slightly less than the amount indicated at "a" in Fig. 1.

It is to be observed in Fig. 8 that after the removal of the draft gear and yoke assembly from the press, the distance between the front and rear stop lug engaging faces, 14e and 35, of the main follower and rear follower, respectively, is greater than the distance between the front stop lugs 2-2 and rear stop lugs 4-4 of the draft gear pocket. This occurs because upon removal from the press the main cushioning unit 8 which has been held under compression is free to expand until the shoulders 25b on compensating follower 22 engage surfaces 17 on the head of the yoke. In this position of the parts, the main cushioning unit 8 remains under substantial compression.

The draft gear and yoke assembly is now ready to be placed in position within the draft gear pocket. The assembly is raised until its position relative to the draft gear pocket is similar to that shown in Fig. 8. It will be observed that the aforementioned tapered surfaces 14g and 38 of the main follower 14, and rear follower 31, respectively, are in position for engaging the lower extremities of the draft gear pocket stop lugs upon upward movement of the draft gear assembly. It will be observed that the forward surface 43 of the yoke is clear of rear surface 45 of striking casting 5. Upon the application of sufficient upward force to the assembly the wedging action of surfaces 14g and 38 moves the main follower and rear follower towards one another allowing the assembly to be raised into the draft gear pocket. As the followers are moved towards one another during this operation, the yoke is freed for limited longitudinal movement, thereby allowing it to be moved rearwardly and assuring sufficient clearance between nose 43 of the yoke and portion 45 of the striking casting.

After the yoke and draft gear assembly has been forced into position within the draft gear pocket, the usual yoke or draft gear support plate 39 can be secured to the car sills 1-1. The coupler shank 7 may then be inserted into the yoke, the draft gear key 9 applied, and the shims 37 removed, whereupon the compensating follower

22 moves forwardly into engagement with the rear abutting surface 27 of the coupler shank 7, thus placing the draft gear in tight engagement with the yoke.

It will be noted that the draft gear is now in tight engagement with front and rear stop lugs 2-2 and 4-4 of the pocket and it is also in tight engagement with the yoke. While at the rearward end the yoke directly engages the gear, at the forward end the engagement takes place through the coupler shank 7 and yoke connecting key 9. It will be clear that end surface 27 of the coupler shank functions in the same manner as though it were an integral front abutment in a yoke, the operation of the draft gear being the same in either case.

An alternate method of assembling the mechanism is illustrated in Fig. 10 in which slugs 45 and 48 are inserted into the positions shown, while the draft gear parts are being assembled in the yoke. The slugs are of such dimensions that they may easily work themselves out between existing clearances and will not hang up within the gear. Also these slugs may be made of a suitable crushable material. Prior to the insertion of the main group 8 of cushioning pads, the rear positioning slug 48 is inserted between the rear surface 34 of the rear follower 31 and the pulling surface 30 of the yoke, and is positioned at a point centrally located with reference to the rear surface 34.

It is necessary that the length of slug 48 be at least as great as the amount of offset, as shown at "a" in Fig. 1. This positions the yoke a sufficient amount rearwardly so that the nose 43 thereof will clear portion 45 of the striking casting when the assembly is raised into the draft gear pocket.

The draft gear and yoke assembly is then placed in a press and the main cushioning unit 8 and the compensating cushioning unit 10 are inserted in the manner previously described. Thereafter, the force is released from the draft or stop lug engaging faces 14e of the main follower and is reapplied to the coupler engaging portion 24 of compensating follower 22. The force should be sufficient to allow for the insertion of the front positioning slugs 45 between the rear surfaces 17 of the yoke head and shoulders 25b of the compensating follower. The length of slugs 45 is such that after the force of the press upon the compensating follower has been released, the distance between the stop lug engaging faces 35 and 14e of the rear and main cushioning followers, respectively, is less than the distance between the front 4-4 and rear 2-2 stop lugs of the draft gear pocket.

The draft gear and yoke may then be removed from the press and raised into position within the draft gear pocket, after which the support plate 39 may be secured to the car sills 1-1. Next the coupler shank 7 is inserted into the yoke and the draft gear key 9 applied. The front and rear slugs may then be easily removed by subjecting the draft gear to several substantial buffing blows, thus releasing the pressure on the slugs and allowing them to drop clear of the mechanism.

Disassembly of the mechanism is effected as follows: Shims 37 are utilized during this operation, the wedge portions 40 thereof being inserted from the underside of the mechanism into recesses 14h in main follower 14 and the shims then being driven upwardly, thus forcing the compensating follower 22 rearwardly out of en-

gagement with end surface 27 of the coupler shank 7. This facilitates removal of the draft gear key 9 and permits withdrawal of the coupler shank from the yoke. The yoke support plate 39 may then be removed, after which the draft gear and yoke assembly can be forced out of the draft gear pocket by means of pry bars or other suitable implements.

It will be noted that the composition and thickness of the rubber pads, the number of pads, and the distance between the main cushioning follower 14 and rear follower 31 are so arranged that when the draft gear is compressed to its normal assembled length within the draft pocket of the car, the main cushioning unit 8 is under a substantial compressive load of about 20,000 pounds for example. Similarly, the above-mentioned factors and the distance between the compensating follower 22 and the main cushioning follower 14 are such that the compensating cushioning unit 10 is maintained under a compressive load of about 10,000 pounds. The 20,000 pound load reacts, partly, directly against the front and rear draft lugs of the draft gear pocket and partly, to the extent of 10,000 pounds, against both ends of the yoke through the compensating unit. It will thus be seen that the draft gear is held tight in the draft gear pocket and also in the yoke, regardless of the ordinary length variations to which these parts are subject.

In Fig. 3 we have shown our draft gear partially compressed under a buffing load. The rear abutment surface 27 of the coupler shank 7 transmits this buffing load to the compensating follower 22 causing it to further compress the compensating cushioning unit 10 which, as noted heretofore, is pre-compressed under a 10,000 pound load when assembled. As the buffing load increases and the compensating cushioning unit compresses, its resistance correspondingly increases and when it equals the initial compression, 20,000 pounds, on the main cushioning unit 8, the latter starts to compress in series with the compensating unit. As main cushioning unit 8 is compressed, draft lug engaging faces 14c of the main follower 14 leave contact with the front stop lugs 4-4, as shown at 42 in Fig. 3. Further increase in the buffing load causes the compensating and main cushioning units to continue to compress in series until the shock has been completely dissipated.

A feature of our draft gear resides in the elimination of all metal-to-metal limiting stops such as have to be used in friction-type draft gears. Thus the normal running shocks of draft and buff as well as the shocks resulting from abnormal operations or collisions are cushioned by rubber.

Under a pulling or draft load the coupler shank transmits the load through the yoke key 9 and rear pulling surface 39 of the yoke to the rear cushioning follower 31 causing it to move forwardly, thus compressing the main cushioning unit 8. At the same time, because of the forward movement of the coupler shank, the compensating follower 22 moves forward under the expansion of the compensating unit 10 until further expansion is prevented by contact of the compensating follower with surface 14c on the cushioning follower. Thus the pulling force required to start compression of the main cushioning unit 8 is equal to the difference in the pre-compression loadings of main cushioning unit 8 and compensating cushioning unit 10. For the compression values given above a force of 10,000

pounds is required in draft to compress unit 8. As the pulling load increases it causes main cushioning unit 8 to continue to compress until the entire pulling load has been dissipated.

In the form as shown, chosen for illustration of our invention, our draft gear is capable of providing travel in draft of approximately 1 $\frac{1}{8}$ inches and in buff of approximately 3 $\frac{3}{8}$ inches at a loading of 600,000 lbs., as seen in Fig. 5. 10 In the conventional draft gear and coupler application which allows a maximum draft gear travel in buff or draft of 2 $\frac{3}{4}$ inches, the coupler horn 15 is located approximately 3 inches from the front face 46 of the striking casting 5 so that the draft gear may compress its full 2 $\frac{3}{4}$ inches without allowing the coupler horn to contact the striking casting.

In our draft gear, which is designed to use couplers, yokes and car construction made in accordance with A. A. R. standards, we have provided for considerably more than the conventional amount of draft gear travel in buff. We have accomplished this in a very simple and effective manner. As was earlier pointed out herein, the rear follower 31 is formed with a substantial offset between its draft lug engaging portions 35 and its yoke engaging surface 34. It was also pointed out that the coupler or yoke engaging surface 24 of the compensating follower 22 is likewise offset forwardly of the draft lug engaging faces 14c of the main follower 14 by the same amount. This offset construction at both ends of our draft gear provides sufficient clearance between the coupler horn 15 and the front face 46 of the striking casting to enable the coupler to move rearwardly in buff an additional 1 inch over that amount of horn clearance provided for in the conventional draft gear construction.

Fig. 5 shows a typical compression diagram produced by our compensating draft gear. It will be observed that in the range of loads up to about 60,000 pounds such as encountered during stopping, starting and running operations, the travel in buff of our draft gear amounts to approximately 2 inches. It will also be observed that in buff our draft gear provides an additional 1 $\frac{1}{8}$ inches of travel over which to dissipate the shock loads of high intensity.

We have illustrated the application of our compensating "selective travel" draft gear with the well-known A. A. R. vertical plane horizontal key yoke Y-40. It should be understood that any conventional type of yoke of standard length may be used without effecting the novel operation of our draft gear in buff and in draft.

While we have mentioned certain figures which we believe are desirable for the initial compression of the compensating unit and main cushioning unit, it should be understood that these particular values are not essential to the proper functioning of the draft gear. The various parts of this draft gear, the yoke and the draft gear pocket are subject to manufacturing tolerances, and certain of these variations affect the space available for the rubber pads, and necessarily result in deviations from the particular values specified above. The essential requirement is that, under the loosest condition allowed by any combination of tolerances, and variations in the rubber pads, the main cushioning unit should be under an amount of compression greater than the compensating unit so that the gear will fit tightly against the stop lugs of the draft gear pocket.

The terms and expressions which we have em-

ployed are used in a descriptive and not a limiting sense and we have no intention of excluding such equivalents of the invention described or of portions thereof, as fall within the purview of the claims.

What we claim is:

1. A draft gear for assembly with a draft gear yoke and between the front and rear stop lugs of a draft gear pocket, said gear comprising a rearward group of cushioning pads, a forward follower and a rear follower for compressing said pads, said followers having portions engageable with said front and rear stop lugs to place said pads under initial compression upon assembly of said gear in said pocket, said stop lug engaging portions of said forward follower comprising a pair of forwardly extending loop portions, and a forward group of cushioning pads carried by said loop portions reacting against said forward follower and a forward abutment in said yoke, both said forward and rearward groups of pads being compressible in buff, and in draft only said rearward group being compressible.

2. A draft gear for assembly with a draft gear yoke and between the front and rear stop lugs of a draft gear pocket, said gear comprising a forward follower and a rear follower positioned to engage said front and rear stop lugs, a group of cushioning pads under predetermined initial compression for urging said followers into tight engagement with said lugs upon assembly of said gear in said pocket, longitudinally extending loop portions extending from said forward follower, and another group of cushioning pads received by said loop portions, said last-named pads being under predetermined initial compression for holding said gear tightly between front and rear abutments in said yoke, both said forward and rearward groups of pads being compressible in buff, and in draft only said rearward group being compressible.

3. A draft gear for assembly with a draft gear yoke and between the front and rear stop lugs of a draft gear pocket, said gear comprising a main cushioning unit, followers for placing said unit under predetermined initial compression between said front and rear stop lugs, said follower for engagement with said front stop lugs comprising a transverse base portion engaging said unit and a pair of rectangular loop portions extending forwardly from said base portion, the ends of said loop portions being positioned to engage said front stop lugs, said follower for engagement with said rear stop lugs having a portion engageable with the rear abutment in said yoke, and a compensating cushioning unit carried by said loop portions for holding said gear tightly in said yoke, said compensating unit being under predetermined initial compression between said base portion and the forward abutment in said yoke.

4. A railway draft gear comprising a rearward cushioning unit, follower means for compressing said rearward unit, said means comprising followers for engaging the front and rear stop lugs of a draft gear pocket, said follower for engaging said front stop lugs comprising a transverse base portion engaging the forward end of said cushioning unit and rectangular loop portions extending forwardly from said base portion, the ends of said loop portions being positioned to engage the front stop lugs of the draft gear pocket, a compensating cushioning unit received by said loop portions, and a compensating follower received by said loop portions and being engageable with the front abutment of a draft gear yoke, said

compensating unit reacting against said base portion and said compensating follower.

5. A railway draft gear for assembly between the front and rear stop lugs of a draft gear pocket and between the front and rear abutments in a draft gear yoke in which the longitudinal spacing of said abutments is substantially the same as the distance between said front and rear stop lugs, said gear comprising a rear follower having portions for engagement with said rear stop lugs, said follower having a portion offset forwardly of said rear stop lug engaging portions and being positioned to engage the rear abutment in said yoke, a forward follower for engaging said front stop lugs, cushioning means under initial compression between said followers, said front follower comprising longitudinal loop portions positioned to engage said front stop lugs, a compensating follower received by said loop portions and having a surface for engagement with the forward abutment in said yoke, and cushioning means carried by said loop portions interposed between said compensating follower and said forward follower, said last-named cushioning means being under initial compression for urging said compensating follower into tight engagement with said front abutment.

6. A railway draft gear for assembly between the front and rear stop lugs of a draft gear pocket and between the front and rear abutments in a draft gear yoke in which the longitudinal spacing of said abutments is substantially the same as the distance between said front and rear stop lugs, said gear comprising a front follower having a transverse base portion and forwardly extending loop portions positioned to engage said front stop lugs, a rear follower having surfaces for engagement with said rear stop lugs and a rear surface for engaging the rear abutment in said yoke, said rear portion being offset forwardly of said stop lug engaging surfaces, a group of resilient pads under initial compression between the rearward side of said base portion and said rear follower to urge said loop portions and said rear follower into tight engagement with said stop lugs, a group of resilient pads carried by said loop portions and engaging the forward side of said base portion, and a compensating follower carried by said loop portions interposed between the forward end of said last-named pads and the front abutment in said yoke, said last-named pads being under initial compression to urge said rear follower and said compensating follower into tight engagement with said yoke abutments.

7. A railway draft gear for assembly between the front and rear stop lugs of a draft gear pocket and between the front and rear abutments in a draft gear yoke in which the longitudinal spacing of said abutments is substantially the same as the distance between said front and rear stop lugs, said gear comprising a front follower having a transverse base portion and forwardly extending loop portions positioned to engage said front stop lugs, a rear follower having surfaces for engagement with said rear stop lugs and a rear surface for engaging the rear abutment in said yoke, said rear surface being offset forwardly of said stop lug engaging surfaces, a group of resilient pads interposed between said base portion and said rear follower, said pads being under initial compression to urge said loop portions and said rear follower into tight engagement with said stop lugs, a compensating follower carried by said loop portions and being movable longitudinally thereof, a group of resilient pads carried by said loop

portions interposed between said base portion and said compensating follower, said compensating follower extending forwardly of said loop portions and being urged into tight engagement with said front abutment in said yoke by said last-named resilient pads upon assembly of said gear in said yoke.

8. A railway draft gear for assembly between the front and rear stop lugs of a draft gear pocket and between the front and rear abutments in a draft gear yoke in which the longitudinal spacing of said abutments is substantially the same as the distance between said front and rear stop lugs, said gear comprising a rear follower having portions for engaging said rear stop lugs, said follower having a yoke engaging portion offset forwardly of said stop lug engaging portions, a group of resilient pads engaging said follower, a forward follower engaging said pads and having loop portions for engagement with said front stop lugs, said pads being compressible upon forward movement of said rear follower by said yoke, a forward group of pads engaging said forward follower and being arranged in series with said first-named pads, a compensating follower interposed between the forward abutment in said yoke and said said forward group of pads, said compensating follower being movable rearwardly to compress said groups of pads, said forward group of pads and said compensating follower being carried by said loop portions, said compensating follower extending forwardly beyond said loop portions and being urged into tight engagement with the forward abutment in said yoke upon assembly of said gear in said yoke.

9. In railway draft rigging a draft gear pocket having front and rear stop lugs, a draft gear in said pocket, said gear comprising a front follower engaging said front stop lugs and a rear follower engaging said rear stop lugs, a cushioning unit under predetermined initial compression between said followers, said front follower having a pair of longitudinal loop portions engaging said front stop lugs, a compensating cushioning unit carried by said loop portions, and a compensating follower for compressing said compensating cushioning unit, a yoke encircling said gear and having a rear abutment engaging said rear follower, said yoke engaging portion of said rear follower being offset forwardly of said rear stop lugs, a car coupler having a shank portion operatively connected to said yoke, the end of said shank portion having an abutment surface positioned forwardly of said front stop lugs by an amount equal to the forward offset of said yoke engaging portion of said rear follower, said compensating cushioning unit being under predetermined initial compression for urging said compensating follower into tight engagement with said shank abutment surface.

10. In a railway draft gear a pair of relatively movable followers, one of said followers having a transverse base portion and a pair of loop portions extending forwardly longitudinally from said base portion, each of said loop portions comprising upper and lower arms, the other of said followers being carried by said loop portions and having a surface positioned to engage an abutment in an associated draft gear yoke, and resilient means carried by said loop portions and being compressible between said base portion and said other follower, the outer sides of the upper and lower arms of each of said loop portions being recessed to allow insertion of shims there-
in for engaging portions of said other follower

during assembly of said gear in a draft gear pocket to maintain said yoke engaging surface in predetermined position rearward of an abutment in the associated yoke.

11. A railway draft gear comprising a pair of relatively movable followers, one of said followers having a transverse base portion and a pair of loop portions extending forwardly longitudinally from said base portion, the other of said followers being received by said loop portions and being movable toward and away from said base portion, resilient means interposed between said base portion and said other follower, the outer side of each of said loop portions being recessed in a vertical direction to allow insertion of shims therein for engaging said other follower to maintain the latter in predetermined relationship to said first-named follower against the resistance of said resilient means during assembly of said gear in a draft gear pocket.

12. A railway draft gear comprising a pair of relatively movable followers, one of said followers having a transverse base portion and a pair of loop portions extending forwardly longitudinally from said base portion, the other of said followers being carried by said loop portions and being movable toward and away from said base portion, resilient means interposed between said base portion and said other follower, said other follower having abutment means arranged adjacent the inner sides of said loop portions for engagement with an assembly slug for urging said followers inwardly of the draft gear when the gear is within an associated yoke.

13. A follower for a railway draft gear, comprising a pair of stop lug engaging portions, a draft gear yoke engaging portion offset forwardly of said stop lug engaging portions, and tapered portions at the upper ends of said stop lug engaging portions adapted for wedging engagement with the associated stop lugs of a draft gear pocket upon raising of the draft gear, during the assembly of the gear in a car, to bring said stop lug engaging portions into contact with the associated stop lugs.

14. A follower for a railway draft gear, comprising a pair of spaced transversely extending rectangularly shaped abutment portions, the rearward one of said abutment portions having vertically extending notches at the lateral extremities thereof for guiding an associated assembly shim into place, the forward one of said abutments being of such dimensions as to be received within the head of an associated draft gear yoke during assembly of the draft gear in the yoke, and abutment means positioned to engage the head of the yoke to limit the extent to which said forward abutment portion is received in the yoke head.

15. A follower for a railway draft gear, comprising a transverse base portion, a pair of longitudinal loop portions extending in one direction from the lateral extremities of said base portion, the ends of said loop portions having vertical surfaces for engagement with the stop lugs of a draft gear pocket, said loop portions having tapered surfaces adjacent the upper ends of said vertical surfaces and forming continuations thereof, said tapered surfaces being positioned for wedging engagement with said stop lugs upon raising of the draft gear, during assembly of the gear in a car, to bring said vertical surfaces into contact with said stop lugs.

16. A railway draft gear comprising a plurality of follower members, certain of said mem-

bers having surfaces positioned to engage the front and rear stop lugs of a draft gear pocket, resilient means for opposing relative longitudinal movement between said members, said members being so arranged that the distance across the front and rear stop lug engaging surfaces of said members upon assembly of said draft gear in a yoke being greater than the longitudinal spacing of the front and rear stop lugs of the pocket, said stop lug engaging members having inwardly tapered surfaces at the upper ends thereof for wedging engagement with the front and rear stop lugs of the pocket upon raising of said gear and yoke, during assembly thereof in a car, to force said members inwardly of the gear and thereby enable movement of said gear into the pocket.

17. A railway draft gear comprising a pair of relatively movable followers, one of said followers having a transverse base portion and portions extending forwardly from the lateral extremities of said base portion for engagement with the draft lugs of a railway car draft gear pocket, the other of said followers arranged between said forwardly extending portions and being movable toward and away from said base portion, and resilient means interposed between said base portion and said other follower, said followers having opposed abutment means for en-

gagement with an assembly shim for holding said resilient means compressed during the insertion of said draft gear into said draft gear pocket.

- 5 18. In a draft gear of the compensating type a pair of relatively movable followers and resilient shock absorbing means between said followers arranged to compress and expand upon movement of one follower relative to the other of said followers, one of said followers having forward extensions for engagement with draft lugs of a railway car draft gear pocket and the other of said followers being arranged between said extensions, said last-named follower and said extensions having opposed abutment means for engagement with an assembly shim for temporarily holding said resilient means compressed between said followers for assembly purposes.
